CLAIM

The ornamental design for a combined divider panel and food storage container, as shown and described.

DESCRIPTION

FIG. 1 is an exploded perspective view of a combined divider panel and food storage container, showing my new design;

FIG. 2 is a front elevational view of the divider alone, shown with the food storage container removed to show aspects of the divider not visible when combined;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
